Vincent Vogel
INVENTOR
BY Arnold M. Schrlich
ATTORNEY

UNITED STATES PATENT OFFICE.

VINCENT VOGEL, OF CHICAGO, ILLINOIS.

FASTENER.

Application filed November 25, 1927. Serial No. 235,599.

This invention relates to new and useful improvements in fasteners and more particularly to a fastener which is especially adapted for use in connection with neckties. One of the objects of my invention is the provision of a device of the above character wherein a necktie can be quickly arranged in position and securely held against displacement.

Another object of the invention is the provision of a fastener of the above character which can be quickly associated with a necktie and so constructed as to retain the tie in its proper associated position, relative a collar to which it may be attached.

With the above and other objects in view the invention consists in the novel features of construction, the combination and arrangement of parts hereinafter more fully set forth, pointed out in the claims, and shown in the accompanying drawings, in which

Figure 1 is a front elevation of a necktie showing the use of my invention.

Figure 2 is a rear elevation of a tie showing the application of my device.

Figure 3 is a side elevation of the device itself.

Figure 4 is a top plan view.

Figure 5 is a cross section on the line 5—5 of Figure 3, and

Figure 6 is a detail side elevation showing how the elastic is engaged with the collar button.

In carrying out my invention, it will be noted that in the accompanying drawings I have illustrated a type of four-in-hand tie, as indicated at 1 to which my improved fastener is applied. The fastener itself is made of any size wire suitable for the purpose and is bent to form the particular type of fastener desired. In the present instance the fastener includes the longitudinal body part 2 having lateral wings 3 and 4 extending from one end thereof upon opposite sides of the body, said wings being slightly curved as shown in Figure 4.

The end of the body opposite the wings is provided with the apposed loops 5 and 6, arranged upon opposite sides of the central portion of the body part 2. The body 2 which is formed of several strands of the wire of which the device is constructed and these strands are securely held in place by coiling a wire 7 around them, which is of smaller diameter than the wire of which the device is formed and possesses more flexibility.

The main portion of the fastener may be

attached to rear side of a four-in-hand tie, as shown in Figure 2 and this can then be fixed in position on a collar and secured in place by means of an elastic loop 8, the ends of which are secured in place beneath the wire 7, as shown in Figure 3. When the tie has been placed in its proper position relative the collar, as shown in Figure 3, the loop 8 is brought upwardly over the cross piece 9, which connects the loops 5 and 6 and is then engaged over the collar button 10, as illustrated in Figure 6.

It will be apparent from the above that I have provided a simple and inexpensive device of the character set forth, which is very efficient for the purpose intended. In use the fastener is attached to the rear face of the tie in any manner desired and when placing the tie in position the wings 3 and 4 are positioned between the folds of the collar and the bow or tied part of the tie positioned between the ends of the outer fold as shown in Figure 1. After the wings 3 and 4 are properly positioned the loop 8 is then drawn upwardly and engaged over the head of the button 10, which holds the ends of the collar in place. From this it will be noted that the tie will be securely held in its proper position, relative the collar and can be quickly and easily placed in position or removed.

While I have described and illustrated the preferred embodiment of my invention, it will be apparent that various changes and alterations may be carried out without departing from the spirit of the invention or the scope of the appended claims.

I claim as my invention:

1. In a device of the class described and in combination, an elongated body part, yieldable curved wings extending from opposite sides of the body at one end, apposed loops at the other end, and an elastic strip having its ends extended through the loop and secured to the body, and its intermediate portion forming a loop for engagement with a supporting element.

2. In a device of the class described and in combination an elongated body part, yieldable curved wings extending from opposite sides of the body at one end, apposed loops at the other end, and a yieldable retaining element engaged with the loops.

In witness whereof I have hereunto set my hand this 21st day of November, A. D. 1927.

VINCENT VOGEL.
